UNITED STATES PATENT OFFICE.

ALFRED L. ATHERTON, OF PITTSBURGH, PENNSYLVANIA, ASSIGNOR TO WESTINGHOUSE ELECTRIC & MANUFACTURING COMPANY, A CORPORATION OF PENNSYLVANIA.

COMBINED RIVET-HEATER AND RIVETER.

1,376,501.

Specification of Letters Patent.

Patented May 3, 1921.

Application filed September 11, 1920. Serial No. 409,539.

To all whom it may concern:

Be it known that I, ALFRED L. ATHERTON, a citizen of the United States, and a resident of Pittsburgh, in the county of Allegheny and State of Pennsylvania, have invented a new and useful Improvement in Combined Rivet-Heaters and Riveters, of which the following is a specification.

My invention relates to rivet heaters and particularly to rivet heaters of the type wherein the rivets are heated by the passage of electric current through them.

One object of my invention is to provide a combined riveting and rivet-heating machine that shall soften the rivet by the passage of electric current through it and that shall form a head on the softened rivet by the operation of an electromagnet which is connected in circuit with the rivet.

According to modern practice a rivet is softened in one machine either electrically or by means of a coal fire, and then is placed in the piece of material to be riveted and a head formed on the end thereof either manually or by a machine.

In a machine constructed in accordance with my invention, the rivet is heated and a head is formed on the head thereof by one operation, thus the separate step of heating the rivet is eliminated, as is also the operator whose sole duty was that of heating the rivet.

In the preferred machine for practising my invention, an electromagnet of the so-called iron-clad type is connected in circuit with the rivet that is mounted in position for the heading operation. The current flowing through the rivet in series with the electromagnet softens the rivet and the magnetic force of the electromagnet operates a heading member to form a head on the end of such rivet.

In the accompanying drawing,

Figure 1 is a sectional view of a machine constructed in accordance with my invention and

Fig. 2 is a sectional view of a modification of my invention.

Referring to the drawing, two pieces of material 1 and 2 are mounted adjacent to each other and a rivet 3 is placed in position for having a head formed on one end thereof. An electromagnet 4, which is con-

nected to a transformer 5, is provided for forming a head on the end of the rivet 3. 55

The transformer 5 comprises a primary winding 6, which is connected to the conductors 7 and 8 of a supply circuit, and a secondary winding 9. The secondary winding 9 of the transformer is connected 60 in series with the rivet 3, and the energizing coil 10 of the electromagnet 4. The number of turns included in the primary winding 6 may be varied in any suitable manner in order to control the secondary 65 current passing through the rivet 3 and the energizing coil of the electromagnet.

The electromagnet 4 comprises a magnetic shell 11 which surrounds the coil 10 and a core 12 which projects through the coil 10. 70 A heading member 13 is attached to the end of the core 12 and, if so desired, it may be formed integral with such core member. The heading member 13 extends beyond the shell portion 11 as shown in Fig. 1 of the 75 drawing, in order to prevent the engagement of the shell member 11 with the material 1 and 2 that is being connected by rivets.

Upon energization of the transformer 5, the secondary current flowing through the 80 rivet 3, softens such rivet, and simultaneously the energization of the coil 10 attracts the electromagnet toward the plates of material 1 and 2, which in this case must be composed of magnetic material. In such 85 manner, the operation of softening the rivet is performed simultaneously with the operation of heading such rivet. Upon the completion of a head for the rivet 3, the electromagnet 4 may be moved to an adjacent 90 rivet for forming a head thereon in a like manner.

The electromagnet shown in Fig. 2 is similar in operation to the electromagnet shown in Fig. 1 and differs only in a few 95 structural features. Accordingly, like parts in the electromagnet shown in Fig. 2 have been designated by corresponding reference characters.

The electromagnet shell 11 and the coil 10 100 are maintained stationary. The core member 12 is movable relative to the coil 10 and the shell 11 and operates the heading member 13 to form a head on a rivet in the manner above set forth in describing the electromagnet shown in Fig. 1. 105

Modifications in the apparatus, and in the arrangement and location of parts may be made within the spirit and scope of my invention and such modifications are intended to be covered by the appended claims.

5 I claim as my invention:—

1. In a combined riveter and rivet heater, the combination comprising a coil connected in circuit with the rivet to be heated, and 10 means actuated by said coil for forming a head on the rivet upon softening thereof by the flow of current through it.
2. In a combined riveter and rivet heater, the combination comprising a coil connected 15 in circuit with the rivet to be heated, a core armature actuated by said coil, and a heading member attached to said core and actuated thereby to form a head on the end of the rivet.
3. In a combined riveter and rivet heater, the combination comprising a transformer, a coil connected to said transformer in series 20 with the rivet to be heated, and means operated by said coil for forming a head on the rivet upon softening thereof.
4. In a combined riveter and rivet heater, the combination with a supply circuit, a transformer connected to said supply circuit and having a primary and a secondary winding, and a coil connected to said secondary 25

winding in series with the rivet to be heated, of a core armature operated by said coil, and means operated by said core for forming a head on the end of the rivet.

5. In a combined riveter and rivet heater, 35 the combination with a rivet mounted in the material to be riveted and a transformer connected to a supply circuit, of a coil connected to said transformer in series with the rivet, and means operated by the coil for 40 forming a head on the rivet upon softening thereof.

6. In a combined riveter and rivet heater, the combination comprising a transformer, 45 a rivet connected in circuit with said transformer, a coil also connected to said transformer, and means operated by said coil for forming a head on the end of the rivet upon softening thereof.

7. In a combined riveter and rivet heater, 50 the combination comprising an electric circuit connected to the rivet to be heated, an iron-clad electromagnet connected to said circuit, and means operated by said magnet for forming a head upon the end of the rivet. 55

In testimony whereof, I have hereunto subscribed my name this 7th day of September, 1920.

ALFRED L. ATHERTON.
